UNITED STATES PATENT OFFICE.

LOUIS NAIR, OF NEW BRITAIN, CONNECTICUT.

BALL COCK.

1,416,496.

Specification of Letters Patent. Patented May 16, 1922.

Application filed April 8, 1921. Serial No. 459,669.

To all whom it may concern:

Be it known that I, LOUIS NAIR, a citizen of the United States, residing at New Britain, in the county of Hartford and State 5 of Connecticut, have invented certain new and useful Improvements in Ball Cocks, of which the following is a specification.

My invention relates to improvements in ball cocks of the form used for water-closets, and the object of my improvement is to produce a ball cock that will operate to maintain the valve for the water open full for substantially the entire period of flow by having the float operatively disconnected from the valve-closing means during such period of flow except for a brief interval when the tank is substantially filled to the extent desired, when the float engages the said valve-closing means and serves to 15 shut off the water by means of a relatively quick movement, the invention being adapted for use with valves that differ materially as to the details of construction.

In the accompanying drawing:—

Figure 1 is a side elevation of my improved ball cock.

Figure 2 is a plan view of the same.

Figure 3 is a view on an enlarged scale, being part in side elevation and part in 30 section on the line 3—3 of Fig. 2.

Figure 4 is a fragmentary view corresponding to Fig. 3 with the parts in a different position.

Figure 5 a side elevation of a modified 35 form of structure as applied to a valve of different form from that shown in Figs. 1 to 4 inclusive.

Figure 6 is a view part in section and part in side elevation of the supporting 40 bracket and collar shown in Fig. 5.

My improved ball cock is adapted to be supported from the bottom of the tank for a water-closet by means of a threaded nipple 10 on the lower part of the cock body 11 and a clamping nut 12, the said nipple 10 being also adapted to connect with the water supply system.

At the upper end of the cock body 11, and substantially above the nipple 10, is a 50 valve chamber 13 that is provided in the lower part of a head 14.

The head 14 is a sleeve-like structure that is generally vertically directed, and is connected to the nipple 10 by means of a 55 curved elbow 15.

The interior of the head 14 is provided

with a screw thread and extending across the said interior is a bridge plug 16 that serves as the upper wall of the valve chamber 13, separating the said valve chamber 60 13 from the part of the interior open space that is above the said bridge plug 16. The said upper part 21 of the interior open space in the head 14 is in communication with and is virtually an extension of the 65 passage 17 that extends through the elbow 15 and connects at the lower end with the nipple 10.

A port 18 through the bridge plug 16 terminates on the lower face of the bridge 70 plug in the form of a valve-seat 20.

The upper end of the opening 21 in the head or sleeve 14 is closed by a solid cap 22.

The bottom wall of the valve chamber 13 75 is formed by an annular guide plug 23 that has an opening 19 that is below the valve-seat 20 and is of suitable size and form to serve as a guide for the valve 24.

The valve 24 is of cylindrical form and is 80 adapted to cooperate with the valve seat 20.

An arm 25 extends to one side from the head 14, on the side remote from the elbow 15, and has a vertically directed opening 26 that serves as a guide for the float rod 85 27 that extends therethrough.

On the inner side of the elbow 15 is an integral lug 28 that serves as the support for the pivoted end of the valve lever 29, the connection being provided by means of a pin 90 or screw 30.

The said valve lever 29 extends through the downwardly directed and slotted valve stem 31 so as to be adapted to open and close the valve 24 by downward and upward movements and has the outer and free end 32 pivotally connected by means of the pin 33 with the lower end of the float rod 27, the said outer end 32 being substantially in vertical alignment with and below the guide passage 100 26 in the arm 25.

The float rod 27 extends from the lower end 34 upwardly through the guide passage 26 and above the valve structure, has the upper end 35 screw threaded for a positioning 105 and stop nut 36, and has slidably mounted on the intermediate, body portion 37 the float 38, which has an axial opening 39 that is a loose fit for the rod 27.

As shown, the float 38 is of cylindrical 110 form with flat ends 40.

The head 14 has one or more openings 41

in the side wall that serve to connect the valve chamber 13 with the open space of the tank.

In the structure described, the valve 24⁵ closes by an upward movement, corresponding to an upward movement of the float 38.

It will be noted, however, that the valve will remain fully open until the float contacts with the nut 36, a condition that is 10 reached only after the tank has filled nearly to the full extent desired and for which the parts have been adjusted. Then a slight further filling of the tank will suffice for effecting the closing of the valve.

15 In the modification shown in Fig. 5 elbow 15 is omitted; the head 14^a is connected directly to the nipple 10^a; the valve 24^a is operative to close by a downward movement and has an upwardly directed stem 31^a; the 20 valve lever 29^a has one end operatively connected to the said valve stem 31^a, is fulcrumed on a pin 30^a adjacent the middle, and has the other end 32^a connected by means of a pin 33^a to the float rod 37^a; and the supporting arm 29^a that supports the valve lever 25^a is below the said valve lever 29^a.

Accordingly, the lower end portion of the float rod 37^a that extends through the guide passage 26^a is in the form of a downward extension 41 of the rod body 37^a, below the pivotal connection at 38^a.

30 The float 38 operates as in the form described above so as to close the valve by an upward movement of the said float, involving a downward movement of the valve 24^a. 35

I claim as my invention:—

1. A ball cock comprising a body having an inlet and having an outlet provided with a valve-seat, a valve for closing against the said seat, a lever for operating the said valve, 40 a vertically directed float rod connected to the said lever and extending upwardly above the cock structure, guide means for the said rod, a stop device at the upper end of the said rod, and a float slidably mounted on 45 the portion of the said rod adjacent to and below the said stop device.

2. A ball cock as described in claim 1, the said float being of cylindrical form, with a flat bottom or end.

LOUIS NAIR.
